UNITED STATES PATENT OFFICE.

WESLEY WEBBER, OF PITTSBURG, PENNSYLVANIA.

COIN-CONTROLLED GAS-VENDING MACHINE.

SPECIFICATION forming part of Letters Patent No. 548,384, dated October 22, 1895.

Application filed April 18, 1895. Serial No. 545,908. (No model.)

To all whom it may concern:

Be it known that I, WESLEY WEBBER, a citizen of the United States, and a resident of Pittsburgh, in the county of Allegheny and State of Pennsylvania, have invented certain new and useful Coin-Controlled Gas-Vending Machines, of which the following is a specification.

In the accompanying drawings, to which reference is made, Figure 1 is a sectional elevation of my new coin-controlled gas-vending machine, taken on line $x-x$ of Fig. 2, showing the parts in the position they assume when the meter is locked thereby. Fig. 2 is a transverse sectional elevation on line $y-y$ of Fig. 1, showing in diagram the connection of the machine with the meter. Fig. 3 is a plan view of the main crank detached. Fig. 4 is a front elevation of the vending-machine, a portion 20 of the main casing being broken away and showing in sectional elevation a portion of the inclosed mechanism. Fig. 5 is a detailed sectional elevation showing the mechanism arranged for operating a valve or cock in the service-pipe. Fig. 6 is a sectional elevation showing a modification, and Fig. 7 is a sectional plan view of the same on line $z-z$ of Fig. 6.

My invention consists mainly in a coin-controlled gas-vending machine wherein is employed a main gear driven by the power of the meter, which main gear operates a rod, plate, or arm or other pusher designed to dislodge a coin in the machine from a support 30 or table, which dislodgment of said coin either brings another coin into position or allows a locking device or pawl to intercept the progress of the pusher, and thus acts to lock the meter or operate a cock for cutting off the 40 flow of gas.

The invention also consists of the construction, arrangement, and combination of parts, all as hereinafter described and claimed.

A represents the main casing of my new coin-controlled gas-vending machine, designed to be attached to or held in close proximity to a gas-meter B of the usual or of any approved construction.

C represents a shaft reaching from the main casing A into the meter B and connected by a gear-wheel a to another gear-wheel b , so as to be turned by the meter mechanism. The

gear-wheel b may be in addition to the usual meter mechanism or it may be one of the usual gears used for operating the indices of the meter. The opposite end of the said shaft C is provided with a gear-wheel or pinion c , which may be used to revolve the main gear-wheel D directly, or it may be arranged to revolve it indirectly through a pinion d and another gear-wheel e when it is desired to adapt the machine to deliver more or less gas for the coin deposited; in other words, to adapt the machine to a change in the price of gas.

The main gear-wheel D is secured on a shaft f , which is journaled in the main casing, and which, for the sake of economy and to adapt it also to carry an index-pointer g , is bent to form a crank f' . This crank operates a lever E, pivoted at h . The said lever may be variously arranged and variously constructed to be engaged by the crank f' . As here shown, it is formed with a slot h' to accommodate the vertical movement of the crank f' when the same is revolved by the wheel D.

F represents a meter-locking and coin-dislodging plate or pusher, which is reciprocated by the lever E—as, for example, in the construction shown, by a link or pitman connection F'—and slides in a support or box F^2 , formed upon or attached to the back of the main casing, and it serves, first, when intercepted by the pawl L, as hereinafter described, as a lock to the lever E, crank f' , wheel D, gear and pinion d e , (if used,) gear c , shaft C, and gears a b for cutting off the supply of gas, and, secondly, when said pawl is depressed by the presence of a coin between the plunger J and the table K, as hereinafter described, to push such coin out from contact with the pawl, and if more than one coin at a time has been delivered into the primary coin-receptacle G to push them out therefrom one by one as each successive coin's equivalent in gas is consumed.

The primary coin-receptacle G is connected with a chute H, which conducts the coins deposited into its outer open end down to the said receptacle. In said receptacle G is placed a plunger J, provided with a rod or stem J' , which passes through a flange J^2 and out through the top of the main casing, where it projects sufficiently to form an end by which the purchaser may lift it, or it may be pro-

vided with a lifting device—as, *e. g.*, the lever J^3 —for lifting the plunger to clear the delivery end of the chute H , as shown in Figs. 4 and 5. On the stem J' is placed a coiled spring J^4 , which acts between the head J and plate J^2 to normally hold the plunger down, so as to rest upon any coins in the receptacle G , or, in case said receptacle be empty, to rest upon the stop or limit pin j , which comes in contact with the plate J^2 , as shown in Fig. 1, and prevents the plunger from descending beyond bounds.

K represents a table placed beneath the coin-receptacle G , a space i the width of the thickness of a coin being formed between the said table and the lower end of the said receptacle. Protruding through the said table into the said space is a finger i' , formed upon or attached to a lever i^2 and pivoted at i^3 , so that its end i^4 may fulcrum on or beneath the pusher F . The lever i^2 is pivoted to the pawl L , which is formed with a projection i^5 at its free end to intercept the pusher F , as shown in Fig. 1. Said pawl is held up by a spring l . When a coin enters the receptacle G , it disposes itself flatwise upon the finger i' . Said coin may serve by its weight or impact to release the pusher F ; but for greater certainty it is deemed preferable to employ a plunger to press against the coin and finger and release the said pusher F . When the pusher F is thus released, the power of the meter acting through shaft C and gear-wheel c , or c , d , and e , will slowly turn the main gear-wheel D and crank f' , causing the latter to swing the lever E to its opposite position and back to the position shown in Fig. 1. In moving from the position shown in Fig. 1 to the said opposite position the pusher F will push the coin lying next to the table or plate K out of the primary receptacle G , from which it will drop into the cash-box M . The return of the lever E will withdraw the pusher F from contact with the projection i^5 , whereupon (if there be no other coin in the receptacle G) the spring l will project said projecting end of the pawl L into the path of the said pusher F , and thus again lock the meter as before and prevent further delivery of gas.

If more than a single coin be delivered into the coin-receptacle at one time, the coins following the first will, by their own weight or under the pressure of the plunger, prevent the projecting end i^5 of the pawl L from being projected by the spring l , as just described, and will thus delay its interference with the pusher F and the consequent locking of the meter, thus producing the effect that the operation of dislodging the coin and delivering the gas will be repeated automatically so long as the coin remains between the table and the plunger—*i. e.*, until the last coin's worth of gas has been consumed.

The operation of supplying the receptacle G with a coin or coins is simply to retract the plunger by turning the lever J^3 from the position shown in Fig. 1 to that shown in Fig.

4, or otherwise, and then to place the coins, one or more, in the open end of the chute, and then return the lever to the former position, whereupon the spring J^4 will force the plunger and the coins against the finger i' . The number of coins in the receptacle G will be constantly indicated by a scale j' , formed in the rod or stem J' , the surface of the casing H serving as the gage.

In Fig. 5 the pusher F is caused to cut off the gas by turning a valve or cock N in the service-pipe N' and thus prevent the further delivery of gas after the value of the coin or coins deposited has been consumed. In this construction the pusher F is intercepted and locked by a plate O , adapted to be depressed by the coin or coins and plunger in the receptacle G , and connected in this instance to a pivoted rod O' and sustained by a spring o , attached to said rod O' . The plate O is connected to the arm n of the cock or valve by a link n' , so that the pressure of the pusher on O will cause the latter to close the cock and cut off the gas. When the plate O is depressed by the depositing of a coin and releases the pusher F , the cock will be opened by a spring N^2 , arranged to act upon the said arm n of the cock, as will be clearly understood from the drawings.

In Figs. 6 and 7 the coins are pushed out from the coin-receptacle G by a rotating pusher or arm P , which is attached to the main gear D . In this arrangement the main casing A is placed upon the top of the meter B and the gearing is placed in horizontal position, as shown, and connected to the meter by a vertical in place of a horizontal shaft. Figs. 6 and 7 also show a modification of the coin-controlled stop or locking pawl L . As here shown, it is not provided with a pivoted trip-lever; but its upper end, which reaches up through the table K , is flattened to receive the coin upon it, and its outer end extends slightly beyond the walls of the coin-receptacle G .

As above stated, if it is not desired to adapt the machine to be changed for varying prices in gas the gear-wheel e and pinion d may be dispensed with and the wheel c made to mesh directly with the main gear-wheel D ; but when the said gear and pinion are used the pinion d will be journaled on a gudgeon d' , attached to a slotted and adjustable plate d^2 , which may be firmly set against the wall of the main casing by a screw d^3 . The said pinion will be provided with a pair of dowel-pins or equivalent device, on which or by which a larger or smaller gear e may be attached to the pinion d to revolve therewith and to mesh with the main gear D . The adjustability of the plate d^2 permits the ready attachment of interchangeable gears e , so that by simply changing this one gear the machine may be made to deliver more or less gas to correspond with any change in price that may take place.

While I have shown and described my invention as applicable for the sale of illumina-

nating-gas, I do not limit myself to such use, as it may be used for the sale and delivery of water, gas for heating purposes, steam for heating and power, and other liquids or fluids.

5 Having thus described my invention, what I claim as new, and desire to secure by Letters Patent, is—

1. In a coin-controlled gas vending machine a main gear wheel driven by the power of the meter, a coin receiving table, a pusher operated by the main gear wheel for pushing the coins off from said table, and a coin controlled locking device arranged for detaining the pusher and cutting off the gas, substantially as described.

15 2. In a coin-controlled gas vending machine, a main gear wheel driven by the power of a meter, combined with a pusher operated thereby, and a coin controlled locking device for locking the coin pusher, from movement when the coin's value in gas has been delivered, substantially as described.

20 3. In a coin-controlled gas vending machine a primary coin receptacle, a table to support the coin beneath the said receptacle and spaced therefrom, a locking pawl adapted to reach into said space, a pusher arranged to pass through said space, and means for operating said pusher by the power of the meter, substantially as described.

25 4. In a coin controlled gas vending machine a primary coin receptacle, a table or support for the coin beneath the said receptacle and spaced therefrom, and a pusher for dislodging said coin operated by the power of the meter, substantially as described.

30 5. In a coin-controlled gas vending machine a primary coin receptacle, a table beneath the said receptacle and spaced therefrom, a locking pawl reaching into said space, a plunger placed in said receptacle, and a pusher for dislodging the coin from said table operated by the power of the meter, substantially as described.

35 45 6. In a coin controlled gas vending machine, a primary coin receptacle, a table beneath said receptacle and spaced therefrom, a locking pawl reaching into said space, a plunger placed in said receptacle, a device for limit-

ing the downward movement of said plunger, 50 and a pusher for dislodging coin from said table operated by the power of the meter, substantially as described.

7. In a coin-controlled gas vending machine, a primary coin receptacle, a table beneath 55 said receptacle and spaced therefrom, a locking pawl reaching into said space, a plunger placed in said receptacle, a spring for depressing said plunger, a lever for lifting the same and a pusher for dislodging coins from 60 said table operated by the power of the meter, substantially as described.

8. In a coin-controlled gas vending machine a main gear wheel operated by the power of the meter, a coin pusher operated by said 65 main gear-wheel, and a locking device for said pusher, and a cock or valve fitted in the service pipe arranged to be closed by said locking device, substantially as described.

9. In a coin-controlled gas-vending machine 70 a main gear wheel operated by the power of the meter, a crank connected to said gear wheel, a lever connected to said crank, a pusher connected to said lever, a coin receiving table and a locking device arranged to be 75 acted upon by a coin and to intercept and lock the said pusher, substantially as described.

10. In a coin controlled gas vending machine a main gear wheel D, operated by the power 80 of the meter and provided with an arm P, in combination with a table for the coin and a pawl L, arranged to reach above said table and to intercept the arm P, substantially as described.

85 11. In a coin-controlled gas vending machine, the combination with the main gear D, and gear c, attached to a shaft which reaches into and is operated by the meter, of an adjustable plate formed or provided with a 90 gudgeon, a pinion journaled thereon and interchangeable gear wheels adapted to be attached to and revolved by said pinion, substantially as described.
